RAZOR BLADE

Jules Bueno de Mesquita, New York, N. Y., assignor to American Safety Razor Corporation, Brooklyn, N. Y., a corporation of Virginia

Application December 7, 1948, Serial No. 63,960

1 Claim. (Cl. 30—348)

1

This invention relates to safety razor blades, and more particularly to double-edge wafer type safety razor blades made from relatively thin stock.

One of the principal objects of this invention is to provide a safety razor blade of the character referred to which will possess desirable characteristics of an extremely thin blade and also those of a thicker blade.

Safety razor blades of the wafer type, to which the instant invention pertains, are generally used in safety razors which present an outwardly curved (convex) seat or saddle and an inwardly (or concavely) curved cap of substantially the same curvature as the saddle. The blade is placed between the saddle and cap and the two brought tightly together, to cause the blade to flex or conform to the curvature of the coacting saddle and cap.

A second principal object of the invention is to fabricate a razor blade from a steel stock which is relatively thin and so form the blade as to increase its effective thickness without decreasing its flexibility to enable it to readily conform to the saddle and cap curvatures.

An allied object is to provide a wafer blade of the type described having increased capacity to readily and more uniformly conform to the curvature of the razor saddle and cap.

It has long been recognized that the shaving edge, more accurately a narrow portion of the blade bordering the beveled edge, must be held firmly in the razor (i. e., between the saddle and cap) against movement or bending—referred to as “fluttering” in the art.

Another important object of this invention is to provide a safety-razor blade made from thin stock which possesses the additional advantage of increased resistance against undesirable fluttering of its shaving edge.

For the attainment of the foregoing and such other objects as may appear or be pointed out herein, I have shown a preferred embodiment of my invention in the accompanying drawing, wherein:

Fig. 1 is a perspective view of the improved razor blade of this invention;

Fig. 2 is a greatly enlarged transverse section taken in the line 2—2 of Fig. 1;

Fig. 3 is a transverse, sectional elevation through a safety razor, showing the improved blade in operative position;

Fig. 4 is a plan view of the instrumentalities used in producing the improved blade and also illustrating the process thereof; and

2

Fig. 5 is an elevational section taken on the line 4—4.

The improved double-edge wafer blade 5, shown in Fig. 1, presents the customary blade outline including the elongated central cutout 1, the notched corners 2 resulting in the central extensions 3, 3, which are somewhat longer than the shaving edges 4, 4.

The improved blade 5 is made of an extremely thin stock, more particularly, of the order of .006 inch, which is used because it achieves the desired flexibility.

I have found that it is possible to produce a .006 inch blade which will have an increased effective thickness without decreasing its flexibility thereby increasing its body, heft and strength. I have been able to accomplish this by using ribbon stock which is .006 inch thick (designated 15 in Fig. 4) and corrugating the

same to present alternate ridges and furrows, best seen in the enlarged showing of Fig. 2. It will be observed that these corrugations or wavy transverse sections imparted to the blade stock remain throughout of substantially the original thickness of .006 inch.

Since what appears to be a ridge when viewed from one side of the blade becomes a furrow when viewed from the opposite side, the convention is here adopted of describing the ridges and furrows as seen from above. According to this convention, the top ridges are designated 16 and the furrows, 17. The peaks of the ridges 16 are on a common plane defining a uniformly level contacting surface on the blade.

In consequence of the corrugations 16—17, the effective thickness of the improved blade is measured by the distance between the top point of a ridge 16 and the outer (underlying) point of the adjacent furrow 17. This effective distance is, as indicated in Fig. 2, of the order of .007 inch.

This thickness has been referred to as the “effective” thickness because for all purposes the improved blade appears to have a thickness of .007 inch rather than a .006 inch thickness. The height of the corrugations has been exaggerated in the showing of the various figures however only for purposes of illustration.

The corrugations 16—17 extend in the longitudinal direction of the blade, parallel to its cutting edges 4, 4. The second principal object of the invention, as briefly pointed out in the statement of invention, was to embody in a blade having the body or heft of a thicker blade—which is the effective thickness of the improved blade, Fig. 2—and the flexibility of a thinner blade,

As a consequence of the longitudinally-directed alternate ridges 16 and furrows 17, the improved effectively thicker blade is even more flexible for purposes of curvature by the razor clamping members than if it were made of the .006 inch stock without the corrugations.

While the corrugations increase the flexibility of the blade from the standpoint of bending to the curvature of the clamping members, these corrugations also reinforce and rigidify the blade from the standpoint of handling. When the blade is clamped between the blade clamping members, these members engage the tops of the ridges to thus give additionally a more effective rigidity to the terminal shaving edge portions.

It should be observed that the corrugations stiffen the blade in a longitudinal direction, but, on the other hand, increase its flexibility transversely.

By reason of the alternate relation of the ridges and corrugations not only as to their side-by-side disposition but, more particularly, their alternate disposition as viewed from opposite sides, the improved blade readily and facilely conforms to the curvature of saddle and cap, as seen in Fig. 3.

Moreover, the restrictive action of the cap and saddle upon the high points or ridges adjacent to the beveled or cutting edges 4, 4, stiffens these free or distal edge portions and prevents fluttering as pointed out in the statement of invention.

The novel wafer blade is formed by passing ribbon steel stock 15, Fig. 4, which is of the order of .006 inch thickness between a pair of rollers 20, 30, see also Fig. 5, which have circular or ring ridges 27, 37, respectively and alternate circular or annular grooves, respectively 26, 36. The ring ridges and annular grooves are laterally displaced so that the ring ridges 27 of the top roller 20 fit within the annular grooves 36 of the lower roller. As a result, the entering stock 15 is corrugated to form corresponding ridges 16 and furrows 17.

After the corrugations 16-17 are formed in the ribbon stock, it is hardened and beveled to form the cutting edges. It will be observed, best from the enlarged showing of Fig. 2, that the first corrugation, designated 18, 18 adjacent to the two shaving edges 4, 4 are spaced away from these edges. This is to provide straight, uncorrugated edge portions 18^x, 18^x immediately ad-

5 jacent the beveled shaving edges 4, 4 and substantially on the same plane as the peaks of said ridges 16. In order that there be provided these uncorrugated edge portions 18^x, 18^x the two ridged rollers 20, 30, Fig. 5, have annular end portions 28, 38, respectively, which clear the edge portions of the ribbon stock.

10 The width of the uncorrugated end strips or portions 18^x, 18^x are made sufficiently wide to accommodate tolerance variations in the grinding of the beveled edges, without encroaching upon the corrugated portion of the improved blade.

15 Having thus described my invention and illustrated its use, what I claim as new and desire to secure by Letters Patent is:

20 A flexible rectangular safety razor blade of the type having opposed beveled edges parallel to the long dimension of the blade, said blade having formed on each of its opposite faces an undulating surface area centrally lengthwise thereof comprised of alternating furrows and elevations which are parallel to each other and to the beveled edges and extend lengthwise of the blade, all portions of whose cross section 25 taken at right angles to the shaving edges is of the thickness of the original stock for the full length of said cross section, the furrows on one face of the blade underlying the elevations on the other face and being in registration therewith, the thickness of the stock being .006" and the height of said elevations being .001" whereby said stock thickness of .006" will give an effective thickness of .007".
